UNITED STATES PATENT OFFICE.

THOMAS B. COMINS, JR., OF NEW YORK, N. Y.

DEVICE FOR COMPRESSING CORKS.

SPECIFICATION forming part of Letters Patent No. 229,960, dated July 13, 1880.

Application filed June 7, 1880. (No model.)

To all whom it may concern:

Be it known that I, THOMAS B. COMINS, Jr., of the city, county, and State of New York, have invented a new and Improved Device for Compressing Corks; and I do hereby declare that the following is a full, clear, and exact description of the same, reference being had to the accompanying drawings, and to the letters of reference marked thereon, making part of this specification.

This invention is in the nature of an improved device for compressing corks; and the invention consists in a device for compressing corks constructed with two pivoted compressing-jaws to work simultaneously, and with indentations to receive the cork, in combination with a spring to restore the jaws to their normal position, whereby the cork is compressed by its introduction between the jaws or compressors and pressure applied to it.

In the accompanying sheet of drawings, Figure 1 represents a plan or top view of my device; Fig. 2, a longitudinal section of same; Fig. 3, a side view of a modification, and Fig. 4 under-side view of the device, with spring and bottom of hollow base removed.

Similar letters of reference indicate like parts in the several figures.

In compressing the ends of corks to render them soft and elastic for introduction into vials and bottles it is generally necessary to use both hands for that purpose, compelling the druggist or other person to set aside the bottle for which the cork is intended until a cork is fitted to it. To do this, as in the cases of small and filled vials, which are unsteady when standing upright, is inconvenient, and at times results in loss. By my device, however, the corks may be effectually compressed without the necessity of removing the bottle from the hand, since the operation is performed with one hand only.

To this end I construct my device with two compressing-jaws, A A'. These compressors are formed from any suitable material, and they are pivoted at their rear ends to a hollow base, B. The front edges of these compressors have formed in them recesses a to correspond with the different-sized corks the device is to be used for, the recess in one

compressor being opposite the recess in the other. The under side of each of the compressors has cast upon it lugs b, which lugs interlock and lap over the lower edges of the respective compressors, forming substantially a toggle-joint, connecting the compressors at their under sides, and centrally placed and fixed to the under side of the compressors is a spiral spring, c.

Now, my compressing device being constructed substantially as described, it is operated by taking the cork to be compressed in the right hand, inserting it between the recesses a, when by pressing the cork downward the compressors A A' will be forced simultaneously against the surface of the cork, squeezing it, and the cork in this way, being pressed downward two or three times and being turned around slightly within the recesses, so as to present different parts of its surface to the greatest amount of pressure, will be found to be reduced in diameter at its smaller end, softened and rendered elastic, and adapted to the bottle for which it is designed.

It will be observed that this entire operation is performed by one hand, while the other hand may be otherwise engaged.

If desired to exert still greater force for the purpose of compressing the cork, a lever, C, may be secured to one of the compressors, 80 against which the palm of the hand may bear, while the fingers at the same time are pressing the cork downward between the recesses, as before described. (See Figs. 1 and 3.) As soon as the pressure on the corks within the recesses is relieved the spring c restores the compressors to their normal position, ready for another operation.

The simultaneous action of both compressors is effected by the lugs b, which interlock and act as levers, so that pressure applied to one compressor is conveyed to the other in the nature of a toggle-joint.

Having thus described my invention, what I claim as new, and desire to secure by Letters Patent, is—

1. A device for compressing corks, provided with two separately-pivoted compressing-jaws constructed to simultaneously compress the ends of corks by downward pressure applied

thereto and to the corks inserted between the same, substantially as and for the purpose described.

2. In a device for compressing corks, two compressing-jaws pivoted to a hollow base at their rear ends, with corresponding indentations formed in their front edges, and provided with interlocking lugs and a restoring-spring, whereby each of the compressing-jaws 10 may simultaneously compress the corks when inserted between the recesses in their front edges by applying downward pressure to the inserted corks, substantially as described.
3. In a device for compressing corks, two

compressing-jaws, in combination with interlocking lugs, whereby pressure applied to one jaw may be imparted to the other, substantially as and for the purpose described.

4. In a device for compressing corks, two compressing-jaws, in combination with interlocking lugs and a restoring-spring, whereby the jaws may be restored to their normal position, substantially as and for the purpose described.

THOS. B. COMINS, JR.
